UNITED STATES PATENT OFFICE.

FRANCIS B. HENRETTA, OF ROANOKE, VIRGINIA.

TRAFFIC-DIRECTOR.

1,195,583.

Specification of Letters Patent. Patented Aug. 22, 1916.

Application filed May 28, 1916. Serial No. 99,979.

To all whom it may concern:

Be it known that I, FRANCIS B. HENRETTA, a citizen of the United States, residing at Roanoke, in the county of Roanoke, and State of Virginia, have invented certain new and useful Improvements in Traffic-Directors, of which the following is a specification.

This invention has to do with means for directing traffic on city streets and the principal objects thereof are, 1st, to provide an automatic device for displaying traffic signals and one capable of regulation so as to allow variable intervals of traffic in several directions; 2nd, to provide in connection with such devices means for advertising violations of traffic rules.

With such general and other specific objects in view the invention consists in the combination and arrangement of parts as will be herein described and particularly claimed.

In the accompanying drawings, Figure 1 is a diagrammatical representation of the timing and regulating portion of my invention. Fig. 2 a representation in plan view of intersecting streets showing the relative locations of certain of the elements used; Fig. 3 is a wiring diagram in which will be traced the electrical connections by means of which the desired results are obtained; Fig. 4 is a diagrammatical section through one of the safety bars in the street paving showing the means by which the return of the same to normal position may be delayed through a short period of time.

The device is intended for use primarily at intersecting streets, and such a street crossing is shown in Fig. 2, the letters N, W, S and E designating the directions north, west, south and east respectively. The direction of traffic is indicated at each quarter by means of arrows suitably directed in Fig. 2.

At A, B, C and D are located signals or semaphores which control the traffic from north, west, south and east respectively. These are each preferably provided with a visual day signal or semaphore arm, operated electrically and designated A¹, B¹, C¹, and D¹ respectively in Fig. 3 and a night signal or light for use therewith, designated in Fig. 3 as A², B², C², and D² respectively. These lights at night burn constantly and the semaphore arms may carry the customary colored lenses to show "white" and "red" to

indicate that the street is clear or closed to traffic. In connection with these semaphores there is provided a motor M which is suitably geared at 3 and 4 to a drum 5, the gearing being such as to produce a comparatively slow rotation of the drum. The drum 5 is provided with electrical contact bands 6—6 etc., of varying length and suitably wired together at 7—7 etc. There are then provided two contact fingers 8 and 9 which are movable on slides 10 and 11 so as to contact any of the bands 6 desired. The finger 8 serves the semaphores A and C, or for traffic in the north and south directions, the finger 9 serving the semaphores B and D or for westbound and eastbound traffic. Hence by positioning these fingers over bands 6 of various lengths and not completely encircling the drum current will flow to the semaphores for any variable lengths of time desired and be shut off therefrom during regular recurring intervals as may be desired. It will be understood that traffic in one direction may, for example, be open for thirty seconds and closed for a like period, the traffic in the opposite direction being open for say a period of ten seconds while the other stands closed, ten seconds being allowed for clearance of the crossing in each direction. Any such variations may be effected by correct proportions of the drum 5 and the bands 6—6 thereon, the contact fingers being shiftable. The drum 5 is further provided with a continuous band 12 with a contact finger 13, the band 12 being wired to the bands 6—6 at 14 and thus the circuit back to the main source of electrical energy is completed.

In order to safeguard traffic, contact bars A³, B³, C³ and D³ are placed in the street paving, each being provided to warn against violations of traffic rules from the north, west, south and east respectively. These bars are arranged so that if passed over and depressed when the corresponding semaphore shows red all of the semaphores will go to red and in addition a bell 15 and light 16 will be energized at F in the center of the crossing. This signal will continue and the semaphores stand at red for any desired length of time when all signals will automatically be restored and traffic may be resumed and controlled by the normal operation of the device.

The results attained having thus been set forth the wiring and incidental parts by

which the same are secured will now be described, reference being principally to Fig. 3. Any convenient source of electrical energy may be employed, such a circuit being indicated by the conventional electrical symbols + and -. The lights A², B², C² and D² are wired directly across this circuit at 17 and 18, hence as long as current is supplied to the circuit these lights will burn unless cut out by means of a suitable switch in the line. The diagram shows current flowing to the signals B¹ and D¹ which are now "red" and the connections thereto are as follows: from the positive side, through the wires 19 and 20, the winding 46 of the magnetic switch 47 and the wire 48 to the finger 9, the signals being in multiple in this line; through the bands 6, the wires 7 and 14, the band 12 and finger 13 and the wire 21 to the negative side. The signals A¹ and C¹ are similarly wired from the positive side to the drum through the wires 22 and 23, the winding 49 of the magnetic switch 47 and the wire 50. Thus the revolutions of the drum 5 alternately display the signals A¹-C¹ and B¹-D¹. The motor M is wired from the positive to the negative side through the wires 24 and 27, the connector 25 of the magnetic switch 26 normally connecting these wires. The semaphores A and C at this time show "white," hence the bars B³ and D³ guard the northbound and southbound traffic. In case either of these bars is depressed connection will be made between the wires 36 and 37 at 38 or 39, these contacts being in multiple. The magnetic switch 47 functions as follows: Two windings are supplied, these being wound for opposite polarity, the one (46) being in series through the wires 20 and 48 with the signals B¹ and D¹, the other (49) being in series through the wires 23 and 50 with the signals A¹ and C¹. As long as current is flowing to the signals B¹ and D¹ and no current is flowing to A¹ and C¹ the magnetic switch will stand as indicated in Fig. 3 with connection made between the wires 51 and 36 so that the bars B³ and D³ may complete the circuit to the switch 26. If current should be flowing to the signals A¹ and C¹ and not to B¹ and D¹ the reverse condition would exist, the wires 28 and 52 being connected and 36 and 51 disconnected. In this latter case the bars A³ and C³ would be effective and B³ and D³ non-effective.

The bands 6-6 on the drum overlap each other so that during the interval of clearing the crossing all four signals are receiving current so as to hold them at "red." In this case the windings 49 and 46 balance each other and all bars become ineffective so that delayed and slightly premature crossing of these bars will not tie up traffic. But as soon as any signals show "white" the opposite bars are effective. Thus a depressing

of bars B³ or D³ will cause current to flow through the winding of the magnetic switch 26, thence through the wire 32 to the wire 20 and through the regular drum connections to the negative side. The electric switch 26 being magnetized the connection 25 will be broken and the motor M stopped. At the same time the signals A¹ and C¹ will be set through the wire 33, the connector 34 and the wire 35. A second connector 40 of the magnetic switch 26 cuts in the multiple-connected bell 15 and light 16 through the wires 41 and 42.

When the bars A³ and C³ guard the eastbound and westbound traffic the depressing of either of these bars will connect the wires 28 and 29 at 30 or 31, thus cutting in the magnetic switch winding through the wires 29 and 43 to the wire 23 and thence through the regular connections to the drum and to the negative side. The signals B¹ and D¹ go to red because of their being cut across the line through the wires 32 and 44, the connector 45 and the wire 35. The bell 15 and light 16 cut in as before.

While the depression of the bars A³, B³, C³, or D³ is permissible when the traffic over the same is clear, yet a violation of the signal will be instantly advertised and all signals will go to red.

The bars A³, B³, C³ and D³ may be supplied with a suitable "retarding" device such as the commercial check arrangement 53 indicated in Fig. 4 by means of which the bar depressed, such as B³ may be held down and the magnetic switch 26 be held in for any period of time desired so as to allow the violated crossing to become clear. When released and contact broken, the switch 26 automatically returns to its normal position and at once all signals will be reinstated and traffic may be resumed.

From the foregoing description it will be seen that an open circuit causes the semaphores to go to "white," the closed circuit showing "red." Thus in case of accident or shutting off of current all semaphores will go to "white" and traffic may be directed by an officer as usual.

I have thus provided an automatic traffic director suitable for use in cities where congestion exists. And it will be understood that while the embodiment of the invention just described is a practical and desirable one, yet other embodiments are possible within the scope of the appended claims without departing from the spirit of the invention.

What I claim is:

1. A traffic directing mechanism for intersecting streets embodying an electric signal at each of the four corners, and in combination therewith a primary electric circuit, two branch circuits therefrom, each embracing the signals on diagonally oppo-

site corners, and an automatic controlling mechanism for the same whereby the flow of current in the branch circuits may be alternated so as to alternate the display of signals on diagonal corners at and during variable intervals.

2. A traffic directing mechanism for intersecting streets embodying an electric signal at each of the four corners, means for controlling said signals in diagonally opposite pairs, said means comprising an electrical circuit, a rotating drum therein, a series of bands of varying lengths thereon, movable contacts for said bands, each of which has electrical connection with a pair of said signals, the said bands and contacts being so arranged that current will be admitted to one pair of signals before being shut off from the other pair.

20 3. In a traffic directing device an electric circuit, a plurality of lights connected across the same, an electrically actuated mechanical signal for each light, timed means for changing said mechanical signals at variable and recurring periods, said means and said mechanical signals being actuated from the same source of electrical energy as the said lights.

4. In a traffic directing mechanism for intersecting streets, an electric circuit, a plurality of signal lamps in the same, one located at each corner, a motor connected in multiple with the said lamps, electrically operated mechanical signals on each of the four street corners, the diagonal signals being wired in pairs and all being in multiple with the lamp signals, the said motor carrying means for alternating the flow of current between the pairs of signals.

40 5. In a traffic directing mechanism for intersecting streets, an electric circuit, a plurality of signal lamps in the same, one located at each corner, a motor connected in multiple with the said lamps, electrically operated mechanical signals on each of the four street corners, the diagonal signals being wired in pairs and all being in multiple with the lamp signals, the said motor carrying means for alternating the flow of current between the pairs of signals, the said signals being arranged to be displayed when current is admitted thereto and to be withdrawn when the circuit is broken.

6. In a traffic directing mechanism for intersecting streets, an electric circuit, a plurality of signal lamps in the same, one located on each corner, a motor connected in multiple with the said lamps, electrically operated mechanical signals on each of the four street corners, the diagonal signals being wired in pairs and all being in multiple with the lamp signals, the said motor carrying means for alternating the flow of current between the pairs of signals, the said signals being arranged to be displayed when

current is admitted thereto and to be withdrawn when the circuit is broken, the said alternating means being so arranged that one pair of signals will be cut in for a variable length of time before the other pair is cut out.

7. In a traffic directing mechanism for intersecting streets, an electric circuit, a plurality of signal lamps in the same, one located on each corner, a motor connected in multiple with the said lamps, electrically operated mechanical signals on each of the four street corners, the diagonal signals being wired in pairs and all being in multiple with the lamp signals, the said motor carrying means for alternating the flow of current between the pairs of signals, and means located in the paving of one street adapted and connected to short circuit the signals controlling traffic on the other street.

8. In a traffic directing mechanism for intersecting streets, an electric circuit, a plurality of signal lamps in the same, one located on each corner, a motor connected in multiple with the said lamps, electrically operated mechanical signals on each of the four street corners, the diagonal signals being wired in pairs and all being in multiple with the lamp signals, the said motor carrying means for alternating the flow of current between the pairs of signals, and means located in the paving of one street adapted and connected to short circuit the signals controlling traffic on the other street, and a separate tell-tale signal connected so as to be actuated when the said signals are short circuited.

9. In a traffic directing mechanism for intersecting streets, an electric circuit, a plurality of signal lamps in the same, one located on each corner, a motor connected in multiple with the said lamps, electrically operated mechanical signals on each of the four street corners, the diagonal signals being wired in pairs and all being in multiple with the lamp signals, the said motor carrying means for alternating the flow of current between the pairs of signals, and means located in the paving of one street adapted and connected to short circuit the signals controlling traffic on the other street, and a separate tell-tale signal connected so as to be actuated when the said signals are short circuited, and automatic means carried by the said short-circuiting means whereby the said short-circuit may be maintained for a short period of time and then released.

10. In a traffic directing mechanism for intersecting streets, an electric circuit, a plurality of signal lamps in the same, one located on each corner, a motor connected in multiple with the said lamps, electrically operated mechanical signals on each of the four street corners, the diagonal signals

being wired in pairs and all being in multiple with the lamp signals, the said motor carrying means for alternating the flow of current between the pairs of signals, and 5 means located in the paving of one street adapted and connected to short circuit the signals controlling traffic on the other street, and to break the circuit to the said motor.

10 11. In a traffic directing mechanism for intersecting streets, an electric circuit, a motor connected across said circuit, electrically operated mechanical signals on each of the four street corners, the diagonal signals being wired in pairs and the pairs being wired in multiple across the line with a common lead, the said motor carrying means for alternatively connecting either of the pairs of signals with the common lead, short

circuiting means located in the street paving at each corner and adapted to make electrical contact when depressed, whereby the signals in the opposite street will be short circuited, means from the normal circuit to the said signal for making or breaking the 25 connection from the said short circuiting means, the latter being so arranged that the short-circuit connection will be broken when current is flowing to the adjacent signal and closed when current is not so flowing 30 and broken when current is flowing to both pairs of signals.

In testimony whereof I affix my signature in presence of two witnesses.

FRANCIS B. HENRETTA.
